Burnett & Van der Woerd,

Metal Punch,

No. 12,712.

Patented Apr. 17, 1855.

Fig. 1.

UNITED STATES PATENT OFFICE.

M. BURNETT AND CHS. VAN DER WOERD, OF BOSTON, MASSACHUSETTS.

MACHINE FOR PUNCHING METAL.

Specification of Letters Patent No. 12,712, dated April 17, 1855.

To all whom it may concern:

Be it known that we, MARSHALL BURNETT and CHARLES VAN DER WOERD, of Boston, in the county of Suffolk and State of Massachusetts, have invented certain new and useful Improvements in Machines for Punching the Rivet-Holes in the Plates and Flanges of Boiler-Heads, &c.; and we do hereby declare the following to be a full, clear, and exact 10 description of the same, reference being had to the accompanying drawings, making a part thereof, in which—

Figure 1, represents a side view of the machine, and Fig. 2, represents a vertical longitudinal section through the same.

Similar letters in the figures denote like parts.

The nature of our invention consists first in giving the bar that carries the punching tool, a rising and falling motion, parallel to the bed, or bar, that carries the die, so that the hole shall be punched perfectly square through the plate, which would not be the case, if the moving bar were worked from a fixed center.

To enable others skilled in the art to make and use our invention, we will proceed to describe the same with reference to the drawings.

10 A, is the bed or table of the machine, made in any stout substantial manner, and supported on legs or supports B, B. Near the rear of the bed is hung in suitable bearings, a crank shaft C, as also a shaft M, on which a fly or balance wheel N, is placed, and a pinion O, to give motion to the machine. On the shaft C, is placed a cog wheel E, and to the crank F, on said shaft is attached one end of a connecting rod G, the other end of 20 said rod being connected to the rear end of a lever H, which is hung, and has its fulcrum at a, in the brackets I, which are supported on, or may be cast with the bed A.

A link or stirrup b, connects the front end 25 of the lever H, to the front end of the bar J, which carries the punch, and the rear end of the said bar J, rests on a cam c, arranged on a shaft d parallel with that C, before described.

30 On the shaft d, which carries the cam c is placed a gear wheel K, having the same capacity as to circumference and the number

of its cogs, as that of E, which meshes into it, and gives it its motion. The object is to give to the cam c an uniformity of motion 55 with that of the crank F, on the shaft C.

The extreme rear end of the bar J, has a vertical hole through it, which slips over a fixed pin e, in the bed, to allow said rear end to rise and fall, as the shape of the cam may 60 admit. f is a spiral spring, which may or may not be required for holding the bar to the cam, but could only be required in small machines, as the weight of the bar J, of itself will be sufficient to cause it to follow 65 the cam.

The cam c, and crank F, are so arranged on their respective shafts, as that when the point of the bar J, is raised up at its front end by the lever H, it shall receive a similar 70 rising motion at its rear-end by the cam c, and thus always move parallel with the bed, so as to bring the punch down square upon the plate to be punched. If the bar J, moved from a fixed center, as the lever H 75 does, the hole that would be punched by it, would be in the arc of a circle, corresponding to the length of the bar between the punch, and its center or motion. This may appear small in practice, but is sufficient to 80 leave a fin or rough place, at one side of the hole, and the holes of the plates when brought opposite to each other would not perfectly match. But by moving the punch and bar parallel with the bed such contingency is entirely obviated.

85 On the front of the bed A, and bar J, are placed two nibs m m', projecting from the faces of both the bed and bar, and extending out beyond the points of each, as seen in the 90 drawing. The upper nib m, carries the punch n, and the lower one m' the die o. These nibs are so extended out beyond the points of the bed and bar, for the purpose of punching rivet holes in the flanges turned 95 elsewhere in the boiler head, than on its periphery, as for instance the flanges of the flue holes. An ordinary flange on the periphery may be readily punched by a punch and die in the ends of the bar and bed alone, 100 but by the use of the nibs or prolonged portions of the bed and bar we can punch flanges, not heretofore, to the best of our knowledge, punched by machinery. It is

therefore an important feature in our machine, and one which adds materially to its value.

Having thus fully described the nature of our invention, what we claim therein as new and desire to secure by Letters Patent, is—

So combining the punching bar, with a vibrating lever at one end, and a cam at the

other end of it, as that it shall always rise and fall, in a plane parallel to the bed of the machine, substantially as described.

MARSHALL BURNETT.
CHS. VAN DER WOERD.
